UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

CAR CONSTRUCTION.

No. 845,938.

Specification of Letters Patent.

Patented March 5, 1907.

Application filed May 3, 1905. Serial No. 258,577.

To all whom it may concern:

Be it known that I, ETHAN I. DODDS, a citizen of the United States, residing at Pullman, in the county of Cook and State of Illinois, have invented certain new and useful Improvements in Car Constructions, of which the following is a specification.

My invention relates to car constructions, more particularly cars of that type wherein the bottoms are constituted by a series of floor-sections in the form of hinged doors that may be dropped by means of door-operating mechanism to discharge the load beneath or to the sides of the car and subsequently raised to and held in normally closed position.

In an application heretofore filed by me on the 24th day of April, 1905, Serial No. 257,150, I have disclosed as the subject-matter thereof a door-operating mechanism characterized by the provision of a shaft extending longitudinally of each side of the car and provided with offset or cranked portions engaging the under sides of the doors, said shaft being so mounted and operated as to move bodily laterally in a direction transversely of the car-body or inwardly and outwardly of the door, thereby securing a longer and more effective arc of travel to the doors engaging parts. In another application filed by me on the 28th day of April, 1905, Serial No. 257,879, I have shown an extension of the same principle to a car having one or more discharging bottom-sections that are hinged along both their outer and inner edges, so as to dump the load either outwardly or inwardly relatively to the sides of the car. In said last-named application the doors are supported by hinge members carried by 40 slideable longitudinally-extending rods, whereby the hinges on either side may be disconnected to allow the door to drop and swing on the hinges of the other side.

My present invention relates to a car of the same character as that disclosed in the last-named application, my present improvements pertaining to a different manner and means of supporting the inner and outer margins of the drop-bottom sections with capacity for disconnection from their supports, so as to open in either direction, said means being chiefly characterized by the provision of oscillatory rods mounted, preferably, in the side posts of the body and carrying hinge-

arms movably engaging hinge-arms or brackets mounted on the doors.

In the accompanying drawings I have illustrated a preferred mechanical embodiment of my invention as applied to a steel gondola car, and, referring thereto—

Figure 1 is a cross-sectional view of a car, showing a door on one side in open position and the opposite door on the other side in closed position. Fig. 2 is a side elevational view of the end portion of the car shown in Fig. 1. Fig. 3 is a longitudinal sectional view showing in side elevation the door-operating shaft. Fig. 4 is an enlarged cross-sectional view through one side of the car-body, more particularly illustrating the door supporting and operating mechanisms. Fig. 5 is an enlarged detail view in longitudinal section through the shaft-operating mechanism at the end of the car, and Fig. 6 is a detail front elevational view of the shaft-operating mechanism shown in Fig. 5.

Referring to the drawings, 10 may designate the twin center sills, which in cars of this type usually accommodate the draw-bar and coupler.

11 designates the side plates, and 12 the end plates, of the car-body.

13 designates the side stakes, which have outwardly-projecting truss-ribs affording an effective resistance to bending or bulging strains upon the sides of the body.

14 designates each of a series of doors constituting drop-bottom sections of the car-floor. These doors are hinged along both their inner and outer longitudinal edges in the following manner and by the following means: Rotatably mounted in the ribs or webs of the side stakes 13, substantially opposite and in the plane of the doors 14 when closed, are shafts 15, having fast thereon and pendent therefrom a series of hinge-arms 16, carrying at their ends laterally-extending pintles 17. Suitably secured to the outer margins of the doors 14 are hinge members 18, having downwardly-turned or hooked ends 18^a, adapted to engage and hang from the pintles 17 when the doors are closed. A similar mechanism is shown for supporting the inner margins of the doors with the same capacity for a swinging movement on their inner margins as hinges, the same consisting of shafts 19, mounted in the transverse frame members of the car-body, (indicated at 20

and commonly termed "flying transoms,") said shafts 19 being located, preferably, just outside the center sills 10. Fast on the shaft 19 are depending hinge-arms 21, having laterally-projecting pintles 22, adapted to be engaged by the downwardly-turned or hooked ends 23^a of hinge-arms 23, secured to the inner margins of the doors. Preferably, and as more clearly shown in Fig. 4, the hinge-arms 18 and 23 are integral with a bar 24, that underlies and engages the under surface of the door throughout its entire length and constitutes a reinforcement and also a wear-strip or track for the rollers of the door-operating mechanism next to be described.

Disposed longitudinally of and beneath each side of the car-body is a door-operating shaft 25, which has integral offset or cranked portions 25^a, disposed between adjacent flying transoms and underlying the hinged doors. Each shaft has fast thereon a series of spur-gears 26, that rest upon and operate over racks 27, herein shown as bolted to the lower margin of the flying transoms. The offset portions or cranks 25^a of the shaft are each preferably provided with one or more rollers 28, that engage the under surfaces of the doors in an antifriction manner, being so disposed as to register with and operate upon the wear-strips 24. From the foregoing it will be seen that when the shaft 25 is given a turning movement the shaft will not only rotate about its own axis, but by reason of the gear-and-rack mechanism on which it is mounted will be caused to travel bodily and laterally inwardly and outwardly of the sides of the car-body, this resulting in giving to the roller-supports of the doors a long wide arc of travel, permitting a wide opening of the doors, as well as affording a mechanically-advantageous means for operating the latter. Any suitable and convenient mechanism for turning said shaft may be employed, a simple mechanism for this purpose herein shown consisting of the following: Referring more particularly to Figs. 5 and 6, 29 designates a bar securely bolted to the outer face of the transverse end sill 30 and containing a dovetailed channel 31. On said bar is slidably mounted, by means of a dovetailed tongue 32^a, engaging said channel, a block 32, in which is journaled the end of the shaft 25. On the overhanging end of said shaft are keyed a pair of twin star-wheels 33, and between them is loosely mounted an operating-lever 34, that carries on either side a pivoted dog 35, engaging the toothed peripheries of the star-wheels. Pivoted on the block 32, above the inner star-wheel 33, are a pair of oppositely disposed and operating detent-pawl 36 and 37, the noses of which overlie and engage the teeth of said star-wheel, one of said pawls preventing rotation of the star-wheels and shaft in one direction and the other prevent-

ing such rotation in the opposite direction. When both engage the star-wheel in the manner shown in Fig. 6, the shaft is securely held against turning and sidewise bodily movement in either direction.

For the purpose of effecting the oscillation of the outer hinge-shafts 15, so as to connect and disconnect the outer margin of the doors, as desired, one or both ends of the shaft is provided with a depending arm 38, which when swung outwardly of the side of the car-body turns the shaft 15 and carries the hinge-arms 16 and pintles 17 downwardly and out of engagement with the coöperating hinge-arms 18, carried by the door. Conversely, when the arm 38 is swung from the outer inclined position to the vertical depending position, as shown in Fig. 4, said hinge-arms 16 and pintles 17 are swung upwardly into interlocking engagement with the hinge-arms 18. In order to maintain said hinge members in the last-described position, any simple detent mechanism may be employed, such as a ratchet-plate 39, engaged by a pivoted dog 40, which latter is swung downwardly and out of the way when the door is to be disconnected from its hinge. As a further means for locking the hinge-shaft in normally operative position a ring or loop 41 may be pivoted to the side of the car and arranged to engage the lower end of the operating arm 38 when the latter is in its depending vertical position, as clearly shown in Fig. 4, a cross-pin carried by said arm sufficing to retain the latter and the ring engaged with each other.

For operating the inner shafts 19 I may employ at either or both ends thereof an upright arm 43, by rocking which to one side, as shown in dotted lines in Fig. 4, the inner hinge-arms 21 may be dropped, so as to disconnect the hinge-arms 23 from the supporting-pintles 22, thus allowing the inner edge of the door to drop. The reverse movement of said arm 43 after the door has been closed restores the connected condition of said hinge members. Any suitable fastening means may be employed to secure the arm 43 in its vertical or door-operating position.

In operation, assuming that the doors are closed and that it is desired to discharge the load outwardly of the sides of the car, the pawl 40 and locking-ring 41 are disengaged and the arm 38 is swung upwardly, thus rocking the shaft 15 and disconnecting the hinge-pintles 17 from the hinge-arms 18, which allows the door to drop on the hinge-pintles 22 as an axis of movement, when the shaft 25 is actuated by the operating-arm 34 to move said shaft bodily inwardly of the car, the inner detent-pawl being out of the way for this purpose, the weight of the load effecting the actuation of the shaft as soon as it has been started by lever 34. In case it is desired to discharge the load beneath the car, and consequently to swing the doors on their outer

margins as hinges, the inner actuating-arms 43 are operated in the manner described, thus separating the inner hinge members and freeing the inner margin of the doors, permitting 5 the latter to drop as soon as the shaft 25 is actuated in the opposite direction or toward the sides of the car.

To restore the car to normal load-receiving condition after a load has been discharged, 10 whether beneath or to the sides of the car-body, the doors are first restored to horizontal position or closed position by the door-operating mechanism, after which the shafts 15 19, as the case may be, are oscillated to restore the connection of the previously-separated hinge-arms.

It being evident that minor changes in the details of construction and relative arrangement of parts might be made in the above-described mechanism without departing from the principle or sacrificing any of the advantages thereof, I do not limit the invention to the particular structure and mechanism disclosed, except to the extent indicated 25 in specific claims.

This patent is intended to embrace only so much of the disclosure made herein as is covered by the claims.

I claim—

1. In a railway-car having one or more center sills, the combination of one or more dumping-doors on each side of said center sills, separable hinge mechanisms supporting each of said doors on both of its longitudinal edges whereby either edge may be dropped, each of said hinge mechanisms comprising a hinge member carried by the door, an oscillatory hinge-rod, a hinge member for said rod pivotally engaging said first-named hinge member, and means for actuating said hinge-rod, and means for actuating said doors, substantially as described.

2. In a railway-car having one or more center sills, the combination of one or more dumping-doors on each side of said center sills, separable hinge mechanisms supporting each door on both of its longitudinal edges whereby either edge may be dropped, each of said hinge mechanisms comprising a hinge-arm carried by the door, an oscillatory hinge-rod extending longitudinally of the car-body, a hinge-arm carried by said rod, means pivotally connecting said hinge-arms, and means for actuating said hinge-rod, and means for actuating said doors, substantially as described.

3. In a railway-car having one or more center sills, the combination of one or more dumping-doors on each side of said center sills, separable hinge mechanisms supporting each of said doors on both its inner and

outer edges, each of said hinge mechanisms comprising a hinge-arm carried by the door having a bent end, an oscillatory hinge-rod extending longitudinally of the car, a hinge-arm carried by said rod and having a pintle engaging the bent end of said first-named hinge-arm, and means for actuating said hinge-rod, and means for actuating said doors, substantially as described.

4. In a railway-car having one or more center sills, the combination of one or more dumping-doors on each side of said center sills, separable hinge mechanisms supporting each of said doors on both of its inner and outer longitudinal edges whereby either edge may be dropped, each of said hinge mechanisms comprising a hinge member carried by the door, an oscillatory hinge-rod, a hinge member on said rod pivotally and separably engaging said first-named hinge member, and means for actuating said hinge-rod, a detent device for retaining said hinge-rod in a position to hold the door closed, and means for actuating said doors, substantially as described.

5. The combination with a car-body having a dumping floor-section, of separable hinge mechanisms supporting said floor-section on both of its longitudinal edges whereby either edge may be dropped, said mechanism comprising a hinge member carried by the floor-section, an oscillatory rod, a hinge member on said rod pivotally and separably engaging said first-named hinge member, means for actuating said hinge-rod, an operating-shaft having an offset portion carrying a roller, and a wear-strip on the under side of said floor-section engaged by said roller, said wear-strip constituting an integral connection between said hinge members carried by said floor-section, substantially as described.

6. In a railway-car, the combination of a car-body, center sills, one or more dumping-doors on each side of said center sills and forming therewith a substantially level or flush bottom for said car-body, separable hinge mechanisms supporting each of said doors on both of its longitudinal edges whereby either edge may be dropped, each of said hinge mechanisms comprising a hinge member carried by the door, an oscillatory hinge-rod, a hinge member on said rod pivotally engaging said first-named hinge member, and means for actuating said hinge-rod, and means for operating said doors to open and close the same, substantially as described.

ETHAN I. DODDS.
